UNITED STATES PATENT OFFICE.

EDWARD F. TUCKER, OF FREDERICK, MARYLAND.

FRUIT-DRIER.

1,045,643.

Specification of Letters Patent. Patented Nov. 26, 1912.

Application filed August 22, 1911. Serial No. 645,339.

To all whom it may concern:

Be it known that I, EDWARD F. TUCKER, a citizen of the United States, residing at Frederick, in the county of Frederick and State of Maryland, have invented new and useful Improvements in Fruit-Driers, of which the following is a specification.

My invention relates to fruit driers and meat smokers.

10 An object of my invention is to provide a drier that will do its work effectually and cheaply.

Another object of my invention is to provide a drier that is water and fire proof.

15 With the foregoing and other objects in view, my invention consists in such details of construction and in the arrangement and combination of parts as will be hereinafter more fully described and specifically pointed

20 out in the appended claims.

In describing my invention in detail reference will be had to the accompanying drawings wherein like characters denote like or corresponding parts throughout the

25 several views, and in which:—

Figure 1 is a front elevation of my invention, showing a part thereof in section. Fig. 2 is a plan view of the same. Fig. 3 is a side elevation of the same. Fig. 4 is a 30 sectional view taken on the line X—X. Fig. 5 is a side elevation of a drawer. Fig. 6 is a front elevation of the same. Fig. 7 is a plan view of the same. Fig. 8 is a detail view of the frame work of my invention in 35 elevation. Fig. 9 is a sectional view of the frame work taken on the line Y—Y.

In carrying my invention into practice I use a base 1 of plastic material. This base 1 is to be underground and forms the 40 foundation of the drier. A fire box 2 is superimposed over the foundation 1 and is also made of plastic material. The fire box 2 is fed through the door 3 and has a smoke vent 4 leading therefrom. The drier 6 is 45 mounted over the fire box and is to be constructed of metal. The outer portion or shell 6 is to be made of sheet metal while the frame work is to be made of angle and flat-iron. Two flat strips of iron 7 extend 50 from the bottom to the top of the drier. These strips 7 are at the front and are held from the side sheathing by means of the strips 8. These strips 8 extend from front to back and form braces on to which the 55 sheathing 6 is fastened. The ends of the strips 8 are connected by means of the strips

9 which also form braces on to which the sheathing 6 is fastened. Angle-irons 10 are held away from the sheathing 6 by means of the bent strip 11. These strips 11 are fastened to the strips 8 and to the angle-irons 10 and hold the angle-irons 10 the same distance from the sheathing 6 as the strips 7 are held. Angle-irons 12 join the angle-irons 10 and the strips 7 with the 60 angle-irons 10 and make a shelf adapted to receive the drawers 13. Other angle-irons 14 join the strips 7 thereby forming supports on which the angle-irons 12 rest, thus completing the frame and making braces 65 on to which the sheathing 6 may be fastened to, on the drawer side. Angle-irons 15 are placed in between the angle-irons 14. These irons 15 join the strips 7 and also form braces to which the sheathing 6 is fastened. 70 The number of braces on this one side is 75 necessitated by the fact that apertures are cut in the sheathing to receive the drawers 13 and the edges of the sheathing 6 are fastened to these braces 14 and 15.

80 The drawers 13 are also to be made of metal. The corners are joined with wires 16 which act as braces and also help to keep the wire screen 17, which is the bottom of the drawer, from sagging. The handle 18 is fastened to the drawer by means of the 85 rod 19, which passes from one side to the other. This rod not only holds the handle 18 in place, but it also helps to strengthen the drawer. As may be seen by reference 90 to the drawings an air space is left between the drawers 13, and the sheathing 6, which in combination with the wire screen bottoms 17 allows a free circulation of the hot air from the fire in the fire box 2. 95

The smoke vent 4 is provided with a damper 20, near its top. The vent 4 is connected to the drier by means of the pipe 21 which also has a damper 22 therein. The smoke vent is provided with a cap 23 to 100 keep water from entering the fire box from this source.

The drier is provided with hooks 24 near its top to receive an apron, of fire-proof material, which is not shown in the drawings and the use of which will be explained later. Handles 25 are placed on the sides of the drier so that the upper portion may be lifted from the fire box and moved away. A ventilator 26 is provided on the top of 110 the drier.

As I have mentioned before my device

may be used either to dry fruit or smoke meats. When used as a fruit drier the fire is built in the fire box 2, the fruit sprinkled over the bottom of the drawers and the drawers put in place. The damper 22 is closed to keep smoke from the fruit and the damper 20 opened to give the draft. It is to be appreciated that when the invention is to be used for drying fruit, a plate or other member may be employed to close the bottom of the drier. This, however, is immaterial and has not been illustrated in the drawings. As the drawers are all the same size and as the bottom one will heat up the fastest, being nearer the fire than the others, they may be changed around to dry the fruit uniformly.

If it is desired to smoke meat, the drawers are removed and the apron attached to the hooks 24, the damper 20 is closed and the damper 22 opened. The fire is started and the meat hung from the braces. The smoke will enter the box and will escape through the ventilator 26, thereby giving a good draft to the fire as well as effectually smoking the meat. The apron is provided to close the apertures for the drawers and keep the smoke from escaping from this source. If such produce as sausages or chip-beef is smoked, it is placed in the drawers and then the apron is dispensed with.

I desire it to be understood that I may make slight changes in the construction and in the arrangement and combination of parts without departing from the spirit of my invention provided such changes fall within the scope of the appended claims.

Having thus fully described my invention, what I claim as new and desire to secure by Letters Patent, is:—

1. In a device of the character described, a fire box, a drier disposed above said fire box, said drier comprising a sheathing, upright angle-irons disposed within said sheathing, bent strips disposed between said angle-irons and said sheathing, second angle-irons connecting said first named angle-irons and being supported thereby, third angle-irons connected to said first named angle-irons, up-right means disposed within said sheathing adapted to support one end of said third named angle-irons, means disposed between said supporting means and said sheathing, drawers adapted to slide upon said second and third angle-irons for the purpose described.

2. In a device of the character described, a drier, a fire box mounted beneath said drier, said drier comprising a sheathing, handle portions on each side of said sheathing whereby the same may be carried, upright angle-irons disposed within said sheathing, bent strips disposed between said angle-irons and said sheathing, horizontal angle-irons connecting said first named angle-irons and

being supported thereby, third angle-irons having one end connected to said upright angle-irons, said third named angle-irons being horizontally disposed, upright strips disposed within said sheathing and adapted to support one end of said third named angle-irons, means disposed between said strips and said sheathing, a drawer adapted to slide upon said second and third angle-irons, means for admitting heated air within said sheathing for the purpose described. 70

3. In a device of the character described, a stationary fire box, a portable drier disposed above said fire box, said drier comprising a sheathing, said sheathing having handle portions formed thereon, upright angle-irons disposed within said sheathing, horizontally disposed angle-irons connected to and supported by said first named angle-irons, third angle-irons having one end connected to said upright angle irons, vertically disposed strips disposed within said sheathing adapted to support one end of said third named angle-irons, strips disposed between said upright angle-irons adapted to space the same from said sheathing, strips disposed between said vertically disposed strips adapted to space the same from said sheathing, said strips which space said upright angle-irons from said sheathing adapted to be fastened to the strips which space said vertical strips from said sheathing, a drawer slidable upon said second and third named angle-irons, said drawer having a screen bottom, a brass rod extending across the screen bottom of said drawer and adapted to support the same, another reinforcing means extending across the bottom of said drawer adapted to support said screen bottom for the purpose described. 90

4. In a device of the character described, a fire box having a drier superposed thereon and having detachable connection therewith, said drier comprising a sheathing of metal spanned at its upper end by a cover having a ventilator therein, a plurality of drawers slidably mounted within said drier adapted to be spaced from three sides of said sheathing, a pipe having connection with said sheathing communicating with the interior of the drier, said pipe being provided with a damper, a second pipe having connection with said fire box and with said first mentioned pipe for the purpose described. 110

5. In a device of the character described, a fire box having a drier superposed thereon, said drier comprising a sheathing spanned at its upper end by means of an upwardly tapering cover, upright angle-irons disposed within said sheathing, bent strips disposed between said angle-irons and said sheathing, a second angle-iron connecting said first-mentioned angle-iron and being supported thereby, a third angle-iron connected to said first mentioned angle-iron, upright means 125

105

115

120

125

130

disposed within said sheathing adapted to support one end of said third mentioned angle-iron, means disposed between said supporting means and said sheathing, drawers 5 adapted to slide upon said second and third mentioned angle-irons, said drawers comprising a frame work spanned at its lower side by a section of wire fabric, reinforcing wires disposed diagonally across said frame work, a rod journaled through said frame work and having connection with the handle whereby said drawers may be operated for the purpose described.
